UNITED STATES PATENT OFFICE

160,559

SERVING TRAY FOR CRACKERS OR THE LIKE

Tomas H. Spence, Los Angeles, Calif.

Application June 27, 1949, Serial No. 3,571

Term of patent 3½ years

(Cl. D44—14)

To all whom it may concern:

Be it known that I, Tomas H. Spence, a citizen of the Republic of Colombia, residing at Los Angeles, county of Los Angeles, and State of California, have invented a new, original, and ornamental Design for Serving Tray for Crackers or the like, of which the following is a specification, reference being had to the accompanying drawing, forming part thereof.

Fig. 1 is a perspective view of a serving tray for crackers, showing my new design;

Fig. 2 is a top plan view; and

Fig. 3 is a side elevational view thereof.

I claim:

The ornamental design for a serving tray for crackers or the like, substantially as shown.

TOMAS H. SPENCE.
